Res. Attorney.

UNITED STATES PATENT OFFICE.

JOHN D. STEPHENS, OF PITTSBURGH, PENNSYLVANIA.

MEANS FOR HANGING WALL COVERINGS.

1,427,333.

Specification of Letters Patent. Patented Aug. 29, 1922.

Application filed August 4, 1919, Serial No. 315,061. Renewed January 28, 1922. Serial No. 532,504.

To all whom it may concern:

Be it known that I, JOHN D. STEPHENS, a citizen of the United States, and residing in the city of Pittsburgh, in the county of Allegheny and State of Pennsylvania, have invented or discovered new and useful Improvements in Means for Hanging Wall Coverings, of which the following is a specification.

10 My invention consists of new and improved means for hanging tapestry and other wall coverings.

Tapestry is now usually tacked in place on the wall, thus rendering an attempt to take it down fraught with danger of injury to the fabrics. Thus valuable tapestry is frequently permitted to remain in place in an empty house, when it should be taken down and stored away. Also, as in the case of 20 ball or assembly rooms, it is frequently desirable to change the character of the wall coverings to harmonize with the color schemes to be carried out in the decorations for social and other events. Thus it is of 25 great advantage to be able to put up and take down the wall coverings quickly and without damage to the fabrics, since a supply of fabrics to suit the varying needs can be kept in stock by the decorator, and he 30 will be justified in using stuffs of finer qualities if they may be used over and over again without injury.

The object which I have in view is the provision of suitable means for hanging tapestry and other wall coverings in such a manner that the same may be quickly and easily put up and taken down without nailing or tacking through the stuffs and without injury to the same.

40 Generally speaking, my invention consists of a socket molding attached to the wall in a horizontal position, into the recess or socket of which the top or bottom edge of the fabric is inserted, and locking members 45 which are inserted in said socket to wedge the edge of the fabric firmly in place. I prefer to make the locking members of resilient material, such as sheet metal bent to proper form, to gain the necessary spring 50 action for properly gripping the material. The vertical edges of the fabric at the corners of the room are similarly inserted into the sockets of vertical socket moldings fixed in the room corners, and locking members 55 are used to wedge the edges of the fabric in place. The corner socket moldings

are preferably duplex or provided with double sockets and double locking members coacting with the same are used, so that each block will secure in its molding socket the 60 vertical edges of the two adjacent lengths of material.

The socket moldings are preferably concealed by finish moldings to improve the appearance, and the finish moldings are also, 65 preferably, sprung into attachment with the socket moldings, so as to be easily mounted in place or dismounted, when necessary.

Other novel features of construction and arrangement of parts will appear from the 70 following description.

In the accompanying drawings, which are merely intended to illustrate the principles of my invention without limiting the scope of the same to the construction shown, Fig. 75 1 is a broken elevation showing the top edge of a length of tapestry held in place by means of my invention, the finish molding and the tapestry being partially broken away to show the socket molding and the 80 locking members; Fig. 2 is a section taken along the line II—II in Fig. 1; Fig. 3 is a section taken along the line III—III in Fig. 1 with the tapestry also shown; Fig. 4 is a top plan view showing the corner socket 85 molding and the adjacent ends of the finish moldings covering the horizontal socket moldings; Fig. 5 is a section taken along the line V—V in Fig. 4, and Fig. 6 is a broken 90 front elevation of the corner molding with one of the corner locking members in place but with the tapestry omitted for the sake of clearness.

The following is a detailed description of the drawings.

A and A' represent two adjoining walls of a room and B the ceiling. C represents wall covering material, such as tapestry.

To secure the top edge of the tapestry in place, as shown in Figs. 1, 3 and 5, I secure 100 to the wall at the proper height a horizontal socket molding D. This molding is shown close to the ceiling B in Fig. 1 but it may be at a lower level, if desired. In the front face of the molding D is formed a longitudinal socket or recess 1, preferably having a vertically contracted mouth and said molding is provided with a vertical flange or flanges 2 by means of which it may be screwed to the wall as shown. I may form 110 the molding D of resilient sheet metal pressed to proper form, thus obtaining an

elasticity which furnishes a better engagement between the parts. The wall cover is clamped in the socket 1 by a plurality of relatively short locking members or blocks 5 E, formed by bending over resilient sheet metal. These members E are provided with a curved or bellied portion 3 which is adapted to be sprung into the socket 1 of the molding D. If desired, I may provide a single 10 integral locking member for the entire length of the socket molding but I find it more convenient to use a number of relatively short members inserted at intervals. The edge of the tapestry C is inserted in the 15 socket 1, as shown in Figs. 3 and 5 and the members E are forced into place, as shown, thus wedging the edge of the tapestry in place. By pulling out the members E, the fabric is released. The members E preferably 20 have their longitudinal edges upset, as at 4, so that by the application of a knife or screw driver the members may be sprung out of engagement with the socket molding. By using a plurality of short locking members 25 positioned at intervals apart, the tapestry may be properly stretched and smoothly hung, without difficulty.

To conceal the socket molding and the locking members from view, I prefer to use 30 an ornamental sheet metal finish molding F, whose top is provided with a rearwardly extending flange 5 which bears against the wall and covers the top of the socket molding to exclude dust and whose lower edge 35 extends down below the socket molding and performs the same function. The finish molding F may be held in position in any convenient manner. Thus, I show a contracted horizontal double tongue or loop 6 40 which may be forced into the interiors of the locking members E, thus holding the finish molding in place.

The bottom edge of the tapestry is similarly secured in place, the bottom socket moldings being reversed from the position 45 shown in the drawings so that the wedging strain will be exerted downwardly instead of upwardly as in the case of molding D.

At the room corners, I secure the vertical 50 edges of the tapestry in the following manner.

G is a socket molding secured in the corner of the walls A and A' and preferably formed of pressed sheet metal to provide a double socket. Thus 7 represents side 55 flanges which bear against the walls and support the central double socket 8 extending to either side and separated by the stub partition 9 through which screws 10 may be driven to secure the molding G in place. The vertical edges of the tapestry are inserted into the sides of the socket 8 and the double locking members H, of proper form to spring into both sides of the double socket 60 8, inserted in place. The edges of the mem-

bers H are preferably upset as at 11 to facilitate their withdrawal.

To cover and conceal the vertical socket molding G and its locking members H, I provide a finish plate I of rectangular cross 70 section which bears against the vertical edges of the tapestry, and is provided with a double spring tongue 12 which may be sprung into the hollows of the locking members H. 75

It is evident from the foregoing that by means of my socket moldings and locking members tapestry and other wall hangings may be hung or taken down quickly and 80 without trouble.

What I desire to claim is:

1. Means for hanging flexible wall coverings, comprising a molding adapted to be secured to the wall and provided with a longitudinally extending recess adapted to receive the edge of the wall covering, and a plurality of locking members provided with rearwardly bellied resilient portions adapted to be sprung into said molding recess to enable the wall covering to be stretched and secured in place by the insertion of said locking members at intervals along said molding. 85 90 95

2. Means for hanging flexible wall coverings, comprising a molding adapted to be secured to the wall and provided with a longitudinal recess in its exposed face which is adapted to receive the edge of the wall covering, and a plurality of locking members formed by bending up pieces of resilient sheet metal and provided with rearwardly extending protuberances which are adapted to be forced into said recess whereby the wall covering may be stretched and secured in place by the insertion of said locking members at intervals along said molding. 100 105 110

3. Means for hanging flexible wall coverings, comprising a molding adapted to be secured to the wall and provided with a longitudinally extending recess adapted to receive the edge of the wall covering, a plurality of locking members provided with rearwardly bellied resilient portions adapted to be sprung into said molding recess to enable the wall covering to be stretched and secured in place by the insertion of said locking members at intervals along said molding, said locking members being provided on their exposed faces with locking recesses, and a finish molding having on its rear face a locking projection adapted to be inserted into said last named recesses to secure said finish molding in place to conceal said locking members. 115 120 125

4. Means for hanging flexible wall covering comprising a molding adapted to be secured to the wall and provided with a longitudinal recess in its exposed face which is adapted to receive the edge of the wall covering, a plurality of locking members formed 130

by bending up pieces of resilient sheet metal, to provide rearwardly convexed backs and concaved fronts, adapted to be forced into said molding recess whereby the wall covering 5 may be stretched and secured in place by the insertion of said locking members at intervals along said molding, and a finish molding having on its rear face a locking projection adapted to be inserted into the 10 concaved fronts of said locking members to secure said finish molding in place to conceal said locking members.

5. Means for hanging flexible wall coverings comprising a socketed strip secured 15 to a wall and adapted to receive an edge portion of the flexible wall covering, and a resilient locking member provided with a portion adapted to be removably wedged into the socket of the strip to firmly bind the 20 fabric within the socket.

6. Means for hanging flexible wall coverings comprising a socketed strip secured

to a wall and adapted to receive an edge portion of the flexible wall covering, a detachable resilient locking member coactive with 25 the socket in the strip to firmly bind the fabric within the socket, and a finishing strip of sufficient width to conceal the first mentioned strip and the locking member detachably associated with the socket thereof. 30

7. Means for hanging flexible wall coverings comprising a longitudinally socketed strip secured to a wall and adapted to receive an edge portion of the flexible wall covering, and a series of relatively short resilient locking members each formed with a portion adapted to be removably wedged 35 into the longitudinal socket in the strip to firmly bind the fabric within the socket at relatively separated points. 40

Signed at Pittsburgh, Pa., this 26th day of July, 1919.

JOHN D. STEPHENS.
